UNITED STATES PATENT OFFICE.

MAURICE OESTREICHER, OF NEW YORK, N. Y.

DESIGN FOR AN ARTICLE OF MANUFACTURE.

53,602.

Specification for Design.

Patented July 15, 1919.

Application filed April 1, 1919. Serial No. 286,773. Term of patent 7 years.

To all whom it may concern:

Be it known that I, MAURICE OESTREICHER, a citizen of Hungary, and a resident of the city of New York, borough of Manhattan, in the county and State of New York, United States of America, have invented a new, original, and ornamental Design for an Article of Manufacture, of which the following is a specification, reference being had to the accompanying drawing, forming part thereof, which shows my design embodied in a pillow-cover, in which the figure is a front view of my new design.

The design can be applied in numerous other articles as for example, window drapings, scarfs, table covers, and bolster covers.

I claim:

The ornamental design for an article of manufacture, as shown.

MAURICE OESTREICHER.
